CARRYING HANDLE WITH LOCKING FEATURE

Stephen F. Jensen, City Island, N. Y., assignor to American Can Company, New York, N. Y., a corporation of New Jersey

Application May 9, 1955, Serial No. 506,747

5 Claims. (Cl. 206—65)

The present invention relates generally to devices for carrying a plurality of containers and the like and has particular reference to a novel handle which locks into place as a member of a unitary package of containers.

In the marketing of milk in rectangular fibre containers it is often desirable to tie two containers together with a surrounding fibre band to produce a unitary package. A handle is frequently provided for the convenience of the purchaser in carrying the package. The handle very often is a separate member introduced endwise between the containers adjacent their top edges. It has been found that such a free handle sometimes slips out of place and is lost during shipment and therefore is not available for use by the purchaser of the package.

It is an object of the instant invention to overcome this difficulty by the provision of a handle which is formed so as to interlock with the side seams usually provided on milk containers so that the handle is held against displacement in all directions and therefore is always available to the purchaser of the package.

Another object is the provision of such a handle which is economical to manufacture and is readily assembled with the container package.

Numerous other objects and advantages of the invention will be apparent as it is better understood from the following description, taken in connection with the accompanying drawings, discloses a preferred embodiment thereof.

Referring to the drawings:

Figure 1 is a perspective view of a pair of juxtaposed fibre milk containers banded together for carrying as a unitary package by a handle embodying the instant invention;

Fig. 2 is an enlarged fragmentary side view of the containers shown in Fig. 1, the view showing the position of the handle between the containers;

Fig. 3 is an enlarged plan view of a blank from which the handle is made;

Fig. 4 is an enlarged exploded perspective view showing the handle in relation to the side seams of the containers, the containers being broken away and shown in section to more clearly show the relative positions of the side seams;

Fig. 5 is an enlarged sectional view taken substantially along the lines 5—5 in Fig. 2, parts being broken away;

Fig. 6 is an enlarged perspective view of a modified form of handle; and

Fig. 7 is an enlarged sectional view taken through the handle shown in Fig. 6 after being applied to a pair of juxtaposed containers as shown in Fig. 1, the view being taken substantially along the line 7—7 in Fig. 6.

As a preferred or exemplary embodiment of the instant invention the drawings illustrate a handle A (Figs. 1 and 4) for carrying a pair of fibre milk containers B

2

disposed in juxtaposed relation and tied together by a surrounding fibre band C. The containers B preferably are of the character disclosed in United States Patent 2,085,979 issued July 6, 1937 to John M. Hothersall on 5 Container. Such containers comprise a rectangular body D having flat side walls E which at their upper ends are formed with necked-in portions F and an immediately adjacent outwardly or laterally projecting end seam or ledge G which surrounds the periphery of and secures 10 in place a flat top member H.

The body D of the containers B preferably is made from a one-piece flat blank folded along transverse crease lines to provide a tubular rectangular body having the flat side walls E. The marginal end portions of the blank 15 when folded into body shape are overlapped and adhesively secured together to provide a lap side seam J which holds the body together. The side seams J of the bodies are disposed in one of the flat side walls E and extend for the full length of the container from top 20 to bottom, being disposed in the ledge or end seam G, the necked-in portion F as well as the side walls E. The lapped marginal end portions of the body in the side seam due to the thickness of the material from which the body is made, provide a definite step K (see Figs. 4 and 5) on the outside of the container body.

When two containers B are disposed in side-by-side or juxtaposed relation for banding together as shown in Fig. 1, the two side walls E containing the side seams J are arranged directly opposite each other in substantially contiguous relation and the corresponding sections of the ledges G for these side walls thus extend transversely of the package with their outer edges parallel and substantially coincident. In this relation the steps K 30 of the two opposed side seams J are directly opposite each other as best shown in Fig. 5. These steps K are utilized to lock the handle in place as will be hereinafter more fully explained.

The tie band C preferably is made from a single piece 40 of fibre material having its end portions overlapped against one side wall E of one of the containers B as shown in Fig. 1. The overlapped end portions are secured together in any suitable manner, as by wire staples or adhesive interposed between the end portions, to hold the band in place and to thus tie the containers together.

The handle A (Figs. 1 and 4) preferably is made from a one-piece blank 11 (Fig. 3) of heavy stiff paper or cardboard and of generally rectangular configuration. The blank 11 is provided with a centrally located transverse crease or fold line 12 and on each side of the fold line the blank is further provided with handle openings 13. Diagonally opposite corners of the blank 11 are cut away to provide rectangular notches 15, 16 defined by transverse edges 17 which extend halfway across 50 the blank and by longitudinal edges 18, 19 which are located in longitudinal alignment. The notches 15, 16 set off at each end of the blank, longitudinally extending tabs 21, 22 having transverse crease lines 24.

Folding of the blank 11 along its centrally located 60 transverse crease line 12 produces a double layer or thickness handle such as the handle A shown in Fig. 4 in which the fold line is at the top edge of the handle and in which the openings 13 in each layer align or register with each other to provide a hand opening for the handle. 65 In a similar manner the notch edges 18, 19 at the bot-

tom of the handle are substantially coincident and the notch edges 17 align endwise with the tabs 21, 22 depending in edgewise relation from the bottom of the handle.

The two layers of the handle preferably are secured together by a suitable adhesive interposed between the layers. The tab 22 on one layer (at the left in Figs. 2 and 4) is bent at a slight angle under the opposite adjacent layer (at the right) and then is bent upwardly along its crease line 24 to produce a channelled or V-shaped support member 26 having a free upright outer leg, the member extending the full width of the tab 22 and having at its inner end the edge 19 which now constitutes a handle locking edge or element.

In a similar manner the tab 21 on the opposite layer of the handle (at the right in Figs. 2 and 4) is bent at a slight angle under the other adjacent layer (at the left) and then along its crease line 24 is bent upwardly to produce a channelled or V-shaped support member 27 having a free upright outer leg, the member extending the full width of the tab 21 but in an opposite direction relative to the support member 26 and having at its inner end the edge 18 which now constitutes a handle locking edge or element opposed to the handle locking edge 19.

The handle A at its lower end is thus provided with a pair of channel-shaped support members 26, 27 respectively depending from opposed layers of the handle and each support member crossing from its layer beneath the transverse edge 17 of its opposed layer to provide oppositely disposed and oppositely directed positions for the support members as best shown in Fig. 2. The support members thus lock each other against endwise or longitudinal movement in respect to the handle axis. In this relation of the support members 26, 27 their inner, handle locking edges or elements 18, 19 are disposed on opposite sides of the handle but are in transverse alignment.

Hence when the handle A is applied to the unitary package as shown in Fig. 1, it is disposed between the substantially coincident ledges G of the banded together juxtaposed containers as shown in Fig. 2 with the channel shaped support members 26, 27 engaged beneath the ledges in the space between the necked-in portions F of the respective containers. In this position the terminal outer edges of the support members 26, 27 engage against the lower surface of the respective ledges G of the containers and thus support the banded containers while being carried.

In this position of the handle A the handle locking elements or edges 18, 19 at the inner edges of the respective support members 27, 26 align with and engage against the steps K of the container side seams J as shown in Figs. 4 and 5. Since the steps K on the oppositely disposed side seams J, are themselves oppositely disposed in transverse relation and in engagement with the oppositely disposed locking edges 18, 19 on the handle, the handle is securely locked against endwise movement relative to the containers. The handle is also locked longitudinally of the package between the substantially coincident ledges G and also vertically by the support members 26, 27 engaging beneath the ledges G.

The support members 26, 27 being of channel shape, the outer leg of each of the channels yieldably engages against the outer wall of the containers at the necked-in portions F (Fig. 2) by reason of the inherent springiness of the fibre material from which the handle is made and thus effects a wedging of the support members 26, 27 against the outer faces of the necked-in portions F to lock the handle against vertical movement.

In the containers B illustrated in the drawings the side seams J are shown as being arranged with the steps K of the seams directly opposite each other. This is the way the actual containers are made. However it should be understood that the steps K need not be in this aligned

relation and that the invention is equally well adapted by slight relocation of the locking edges 18, 19 of the support members 26, 27 to accommodate the handle A to engage against steps K which are in non-aligned relation.

In some cases it may be desired to reinforce the support members 26, 27 to carry heavier loads. Figs. 6 and 7 disclose such a reinforcement as a modified form of these members. In this alternate form of the invention the tabs 21, 22 in the handle blank 11 shown in Fig. 3 are made slightly longer so as to provide for folding the outer legs of the channel shaped support members back on themselves to produce a double layer leg 31 on each of the members. The layers of these legs may be adhesively secured together if desired. This double layer construction results in added rigidity and strength to the support members.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The combination of a pair of independent rectangular fibre containers having peripheral laterally projecting top ledges, said containers being disposed in juxtaposed relation with portions of said ledges arranged in transversely aligned parallel relation, means for tying said containers together as a unitary package, a handle member interposed between said parallel ledge portions and extending above and below said ledges for carrying said package, said handle member comprising two integral contacting layers of material connected and folded at their upper ends and each layer terminating at its lower end in a tab member at one side defined by a rectangular notch at the opposite side thereof, the tab member of each layer being disposed in registry with the notch of the other layer, said tab members being medially folded upwardly to constitute channel-like container support members of V-shape in cross section respectively extending downwardly through said notches and thence extending upwardly in free ends, each of said support members being locked against longitudinal shifting movement by the adjacent edge of one of said notches, said free ends of said channel-like support members respectively engaging beneath and against said transversely aligned ledge portions of the juxtaposed containers for supporting the containers in carrying position.

2. The combination of a pair of independent rectangular fibre containers having lap side seams each including an exterior step and also having peripheral laterally projecting top ledges, means for confining said containers in contiguous relation with opposed portions of said ledges disposed in transverse registry and with said side seams in adjacently opposed relation to constitute a unitary package, a folded handle member of double thickness interposed between and extending beneath said container ledges for carrying said package, each of said handle member thicknesses terminating at its lower end in an upwardly folded support member at one side thereof set off by a rectangular notch at the opposite side thereof with the support member of each handle thickness extending through the notch of the other handle thickness and extending upwardly on the opposite side thereof to lock said support members against endwise movement towards each other, the free ends of said upwardly folded support members respectively engaging beneath said transversely aligned top ledges of the juxtaposed containers for supporting said unitary package in carrying position.

3. The combination as defined in claim 2 wherein the inner ends of said support members are disposed in

substantial transverse alignment and respectively abut against the aforesaid exterior steps of said container side seams for locking said handle member against longitudinal movement relative to and transversely of said package.

4. A combination of the character defined in claim 2 wherein said containers adjacent said ledges are provided with a necked-in portion and wherein said support members are of channel shape with their free ends engageable against the necked-in portions of said containers for frictionally retaining said handle member in place.

5. A combination of the character defined in claim 2 wherein said support members are of channel shape and the free ends of said support members are of double

thickness for respective reinforced engagement beneath said transversely aligned container ledges for supporting said unitary package.
